UNITED STATES PATENT OFFICE

GEORGE D. COX, OF PHILADELPHIA, PENNSYLVANIA

TELEPHONE-INSTALLER'S OMNIBUS NUMBER SIGN CARD

Application filed April 25, 1930. Serial No. 447,250.

The installation of telephone instruments at the present time has been complicated through the necessity for providing for the numbering of the subscriber's telephones by the installers, who frequently cannot know before leaving the store-house, what numbers the telephones installed must bear. This difficulty is increased also by the different types of instruments having different forms of holders for the number display signs necessitating differently shaped number display signs. Where a series of extensions are used these difficulties are increased.

My invented device is a card that can be carried with other like cards in a bundle by an installer. This card has cut through it a series of discs which are just sufficiently attached to the other portion of the card to remain secured to it and are readily pushed out, which have perforations which allow a portion of the disc to be torn off so that it can fit in a differently shaped holder, the parts separated by the perforations being far more tightly secured to the main portion of the disc than the disc as a whole is secured to the body of the card. The face of the disc is usually a solid dark color to conceal these perforations.

Fig. 1 is a plan of a card containing a series of number displaying discs. Fig. 2 is a plan of same with the discs removed. Fig. 3 is a plan of a disc with the face darkened to conceal the perforation. Fig. 4 is a plan of the disc with its parts that were partly separated from it by perforations, removed so that it will have a shape to fit another holder. Fig. 5 is a view of a modification.

The cards are preferably made in the form of strips which may have the rounded end 2, and the small disc 3, which may be removed if the strips are to be strung on a holder. In this card are the discs 4. These discs 4, and the smaller disc 3, are so slightly secured to the main body portion of the card 1, that they can be pushed out readily and without any danger that by so doing the discs 4, will be torn. In practice, I make a clean cut along the lines *b*, *b*, *b*, *b*, extending practically through the body of the card 1, leav-

ing only a thin sliver of paper attaching these discs to the body. The cut is most advantageously made from the face of the disc.

The face of the disc has on it usually the name of the station and may have merely a blank space for the number of the telephone, or the number may be printed on also at *d*, (see Fig. 1). Both the station and the telephone number may be printed on the disc as shown in Fig. 3, with a blank for an extension.

Perforations 7 and 8, partly sever the central portions of the disc 4, from the wings 9, and 10. These wings may be of any shape by the removal of which the disc 1, may be converted into a shape suitable for fitting into a holder of a different shape from that intended to hold the disc 4. The portions of the paper between the perforations hold the wings 7 and 8 much more firmly to the central portion of the disc 1, than the latter is held in the card 1. The purpose of doing this is to assure that the disc 4, will always be pushed out from the card without tearing it at all along the perforations 7, and 8, and hence spoiling its appearance. The disc having been pushed out from the card the tearing off of the wings 9, and 10, can be accomplished readily, and without trouble, even if they are held rather strongly to the rest of the disc 4. They should be so held because the disc should hold firmly together as a whole when used with the wings attached to it, and the perforations should not appear strongly in it. In Fig. 5 is shown a form of disc 4, viewed from the rear when the wings 9, and 10, are each partly severed from the body of the disc by a cut *f*, which cuts, however, much less deeply into the body of the disc 4 than the cuts *b*, *b*, and does not appear at all on the face. Parts of the device may be omitted, such as the wings 9, and 10, with the omission of their functions and also quite a number of changes may be made in this device which will not depart from my invention so long as they are within a fair construction of the claims.

I claim—

1. A telephone installer's omnibus number sign card, which consists of a card containing

a series of discs, having around the circumferences of each of said discs a cut passing nearly through the body of the card and almost severing the disc therefrom, said discs having wings partially severed from the main portion of the disc but much more firmly attached thereto than the discs are to the card.

2. A telephone installer's omnibus number sign card, which consists of a card in the form of a strip having means whereby this card may be mounted with other like cards on a holder, and containing a series of discs having at the circumferences of each of said discs a cut passing nearly through the body of the card, and almost severing the disc therefrom, and detachable wings forming a portion of said discs.

3. The device as defined in claim 1, wherein the discs have the wings partly separated from the main body of the disc by perforations and having their faces darkened to conceal said perforations.
